US00D614936S

(12) **United States Design Patent**
Petzl

(10) **Patent No.:** **US D614,936 S**
(45) **Date of Patent:** **** May 4, 2010**

(54) **HANDLE FOR CLIMBING APPARATUS**

(75) Inventor: **Paul Petzl**, Barrauz (FR)

(73) Assignee: **Zedel**, Crolles (FR)

(**) Term: **14 Years**

(21) Appl. No.: **29/329,111**

(22) Filed: **Dec. 9, 2008**

(30) **Foreign Application Priority Data**

Jun. 19, 2008 (EM) 000 958681-0001

(51) **LOC (9) Cl.** **08-05**

(52) **U.S. Cl.** **D8/356**

(58) **Field of Classification Search** D8/105, D8/107, 333, 349, 356, 358, 357, 373, 383; D11/200, 215; 24/573.11, 579.09, 579.11, 24/592.11, 599.1, 599.9, 600.1; 182/5

See application file for complete search history.
